ARTISAN TOOL

Bernard J. Davis, Oakland, Calif.

Application October 26, 1932, Serial No. 639,563

6 Claims. (Cl. 33—102)

The invention relates to tools or instruments designed to assist an artisan in reducing to application certain geometrical or trigonometrical problems encountered in the development of his work.

An object of the invention is to provide a tool of the character described which is particularly applicable to carpentry and similar construction work in indicating proper cutting angles for framing and joining timbers or other building members.

Another object of the invention is to provide a tool of the character described which may be applied directly to a building member and when so applied and properly adjusted provides suitable and correctly located straight edges for scribing the proper cutting slants directly on the member.

A further object of the invention is to provide a device of the character described which is simple, inexpensive and compact in construction and has a mode of operation readily comprehended by a relatively unskilled person.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to said drawings:

Figure 1 is a plan view of the tool of my invention.

Figure 2 is a bottom view of the quadrant plate of the tool.

Figure 3 is a sectional view taken substantially on the line 3—3 of Figure 1 with the adjustable arm of the tool removed.

Figure 4 is a fragmentary perspective view of the tool.

Figure 5 is an end view showing the arm construction of the tool.

Figure 6 is an end sectional view taken substantially on the line 6—6 of Figure 1.

Figures 7 and 8 are side elevations of a modified form of the invention.

Figure 9 is a plan view of the modified form of the invention as disclosed in Figures 7 and 8.

Figures 10 and 11 are fragmentary views of a building construction illustrating various timber cuts to which my tool may be adapted.

Referring more particularly to the drawings,

the tool of my invention comprises a quadrantal plate 11 having pivoted thereon for arcuate displacement over the exposed surface 12 thereof an arm 13. Preferably an edge 14 of the plate 11 is so faced that it may abut against a side 5 of a timber with the surface 12 lying substantially coplanar to an adjacent side of the timber. In this way, when moving the arm 13 over the surface 12 of the plate the same may be extended to lie over the coplanar related surface of the timber. It will thus be clear that with the arm positioned on the plate in a certain angular relation to the edge 14, and with the edge 14 placed against a side of the timber, the arm 13 will overlie the timber with the same angular relation as over the plate. By graduating the surface 12 of the plate to obtain such predetermined positions for the arm 13 as are calculated to be of an angular relation to the edge 14 equal to the correct cutting angle for sawing 10 various timbers, the arm 13 may be readily set with respect to the surface 12 for disposing the same for indicating the correct cutting position over the surface of the timber.

Preferably, and as shown, the arm 13 is secured intermediate its ends to the plate adjacent the edge 14 by means of a pivotal connection 15, one portion 16 of the arm being disposed over the surface 12 of the plate while a portion 17 thereof is arranged on the opposite side of the pivotal connection 15 and extends from the edge 14 of the plate to overlie the surface of a timber as aforesaid. An important feature of the structure disclosed is the positioning of the pivotal connection 15 at an edge 18 of the arm, this arrangement causing such edge to pass through the axis of the pivotal connection and in this manner providing on the arm a convenient guide edge and indicia for scribing. This positioning of the pivotal connection is made possible by 20 the use of a laterally extending projection or boss 21 formed on and in outstanding relation to the edge 18 and which is held in pivotal engagement with the plate 11 by means of a pin 22.

In order that the lower as well as the upper 45 surface of the plate 11 may be used with the arm 13, the portion 16 of the arm is desirably extended to the outermost edge 23 of the plate and thence around such end and inwardly over the lower surface 24 of the plate where it connects with the lower end 26 of the pin 22. The extension of the arm thus disposed over the surface 24, and which is indicated on the drawings by the reference numeral 27 is positioned precisely under and in alignment with the main portion 50 of the pin 22. The upper portion 16 of the arm 55 is also positioned to be in alignment with the main portion of the pin 22.

16 of the arm so that upon moving the portion 27 to a predetermined angular position on the surface 24, accurate positioning of the guide edge 18 over the surface of the timber will be assured. Preferably a set screw 25 is carried by the arm portion 27 and arranged to bear against the plate to hold the arm in adjusted position thereover.

With the arm 13 pivoted to the plate 11 and 10 at the same time extending around the edge 23 of the plate, it is desirable, in order to permit relative angular displacement between the arm and the plate, to form the edge 23 of circular contour with the pivotal connection 15 as 15 a center of curvature. Preferably the arm is displaceable over the surfaces of the plate through an arc of substantially 90 degrees, with the edge 23 defining a quadrant starting from adjacent the edge 14 of the plate and extending 90 degrees to a point 28 lying on a line substantially 20 perpendicular to the edge 14 and passing through the pivotal connection of the arm and the plate. Preferably the edge 23 is continued tangentially 25 from the point 28 in parallel relation to the edge 14 so as to define in combination with the curved quadrant portion of the plate a rectangular portion 31 upon which may be tabulated suitable data for use with the tool.

To insure a precise mounting of the tool 30 against a side of a timber, the portion of the edge 14 lying opposed to the curved portion of the edge 23 is provided with a suitable backing element 32 which comprises a vertical straight-edge portion 33 arranged for abutment 35 against a side of the timber, and a laterally extending guide portion 34 which is arranged to lie on the surface of the timber. Preferably the portion 34 extends from the portion 33 intermediate the top and bottom edges 36 and 37 40 thereof and provides a pair of horizontal surfaces 34' and 34'' spaced a distance substantially equal to the depth of the arm 13 and disposed with one of the surfaces 34' substantially coplanar with the surface 12 whereby the backing means will 45 be effective for retaining the edge 14 against the timber with the arm resting on the surface of the timber when either surface 12 or 24 of the plate is exposed position. Preferably the element 32 extends beyond the edge 23 of the 50 plate in order to provide a greater bearing edge than would otherwise be provided, and also the portion of the straight edge 23 lying adjacent the surface 24 may be likewise extended over the full length of the edge 14.

As an important feature of my tool I incorporate, in combination with the arm 13, a longitudinally adjustable arm 41 which provides with the arm 13 when operatively disposed on the surface of the timber a pair of parallelly extending scribing surfaces along the side edges 42 and 43. Connection of the arm 41 to the arm 13 is preferably effected by means of a guide member 44 which forms a right angular extension of the arm 41 at the inner end 46. The guide member is slidably mounted in a groove 47 provided intermediate the opposed top and bottom faces 48 and 49 of the arm 13, and is preferably held against transverse displacement 60 within the groove by means of opposed transverse shoulders 51 and 52 provided on the edges of the arm surfaces 48 and 49 respectively, the shoulders slidably engaging the rear surface 50 of the member 44 and positioned within a groove 55 provided adjacent the opposed side of

the member. Also the arm 13 along the side 53 opposite the guide edge 18 is provided over its entire length with a longitudinally extending opening 54 which registers with the groove 47 so as to thereby permit the protrusion of the 5 arm 41 therethrough. It will be noted that the arm 41 may be reversed so that it may be extended from the guide edge 18 of the arm rather than the edge 53. This reversal is made possible through the use of a side opening 56 provided 10 along the guide edge 18 of the arm 13 and extending from the outer end 57 of the arm a relatively short distance towards the pivotal connection, said opening registering with the groove 47 and permitting the extension therethrough of 15 the arm 41. With the side openings 54 and 56 in the opposite sides 18 and 53 of the arm, and with such openings each extended to the end 57 of the arm, it will be clear that to effect a reversal of the arm 41 it is only necessary to 20 withdraw the guide member 44 from the end 57 and then replace the same in the groove 47 in an inverted position. When used in combination with most of the scales provided on the plate 11, the arm 41 is extended from the edge 25 53 of the arm 13. In certain uses, however, the arm 41 is extended from the edge 18 of the arm and in these uses it has been found that but a small longitudinal adjustment of the arm 41 from the end 57 is required. For this reason 30 the opening 56 provided along the side edge 18 of the arm 13 need only extend but a short distance from the end 57.

Preferably the sides 42 and 43 of the arm 41 are formed of a depth equal to the thickness of 35 the arm 13 whereby the top and bottom surfaces of the arm 41 will lie in the planes of the surfaces 48 and 49 of the arm 13. To provide such an arrangement the arm 41 may be formed as here shown of an I section so as to place the 40 edges of the sides 42 and 43 substantially flush with the surfaces 48 and 49. With this construction, when the arm 41 is moved to the end 57 of the arm 13 there is produced the alignment of the edge 43 on the arm 41 with the end 57 of 45 the arm 13 and the formation of a continuous scribing surface along the guide edge 18, around the end 57 and along the edge 46. Also, due to this formation of the arm 41, the latter is permitted to lie at all times in engagement with the 50 timber surface on which the arms are disposed. This occurs notwithstanding the fact that the arm 41 protrudes through a side opening in the arm 13, which arrangement would normally require the arm 41 to be held spaced from a plane 55 surface on which the arm 13 was disposed.

It is of importance, in the various uses of the tool, that the distance between the arm 41 and the edge 14 be determinable. In order that this distance may be readily ascertained, the top and bottom surfaces 61 and 62 of the guide member 44 are graduated longitudinally of their length starting with zero at the outer end 43 and are visible through an opening 63 provided through the top 48 of the arm 13. To facilitate the longitudinal adjustment of the member 44 with respect to the edge 14 in the various angular positions of the arm 13, the portions 66 and 67 of the arm 13 lying adjacent the opening 63 are provided with transversely extending graduations 68 70 which overlie the edge 14 and with which the graduations on the member 44 may be aligned. Thus since the graduations 68 and those on the member 61 extend transversely to the length of the arm, the distance say from the edge 43 along 75

the side 18 to the edge 14 may be readily determined by following the graduations 68 on the portion 67 which extends to the edge 14, at the intersection of the side 18, inwardly to the scale 61 where the desired distance may be directly read. Similarly the distance of the edge 42 from the side 14 along the edge 18 may be found by subtracting the width of the member 41, or the distance between the sides 43 and 42 from the side 14 along the side 13 may be similarly found by the use of the graduations 63 on the portion 66.

Means are preferably provided for retaining the member 44 in desired longitudinal adjustment, and as here shown such means is shown in the form of a shoe 71 which is carried by the pin 22 forming the pivotal connection between the arm 13 and plate 11. The shoe may be pressed against the exposed surface of the member 44 by means of a wing nut 72 which is threaded on an end of the pin.

In Figures 7 and 8 of the drawings I have disclosed a slightly modified form of the tool. In this embodiment the curved edge 23' of the quadrant plate is provided with an enlarged vertically disposed end face 98 on which may be arranged certain graduated scales 100. With this construction the rearwardly extending end 16' of the arm 13' is bent upwardly from the surface 12' of the plate and extends over the graduated end face 95 to provide an indicating member 96. A set screw 97 is preferably carried by the portion 16' for releasably holding the arm 13' in adjusted position over the surface of the plate. In this embodiment the portion 26' of the arm which is disposed over the lower surface 24' of the plate is not connected to the outer end of the arm portion 16' as in the first embodiment, but is preferably held in alignment with the arm portion 16' for rotation therewith by means of a pair of square portions 98 and 99 provided on the pin 22 and engaging in similarly formed openings of the arm portions 12' and 24'.

In illustrating the use of my tool I have shown in Figures 10 and 11 of the drawings, fragmentary views of building roof structures requiring certain angularly cut timbers in their construction. In the present embodiment of the invention the scales provided on the surfaces of the plate 11 have been especially designed to render the tool applicable for marking the cuts for the various timbers used in the structures shown. Each of the scales has therefore been graduated in terms of the roof pitch of the structure, so as to provide for the proper setting of the arm 13 to give the correct angle for scribing the different individual cuts on the timbers for roof pitches varying from one to 24" rise per foot. Thus in setting of the tool for scribing the plumb cuts 101 at the top of a common rafter such as illustrated by the timbers 102, the arm portion 16 is moved over the surface 12 to position the guide edge 18 of the arm opposite the figure indicating the appropriate roof pitch in the arcuate arrangement of graduations labeled as "plumb cuts of common rafters." With the arm thus positioned, the tool may be applied to a timber and the latter marked in the manner heretofore described. In a similar fashion the arm may be set for scribing the plumb cuts 103 on the hip rafters 104, for marking the side cuts 106 on the hip rafter 104, and for scribing the face and side cuts of roof boards. Also the tool may be set for scribing the side cuts 107 in the jack rafters 108, and for scribing the foot cuts

111 and the toe cuts 112 in the common, hip and jack rafters. Scribing the top cuts 113 of the raking molding 114, and the backing cuts 115 on the hip rafter 104, as well as the plumb and cheek cuts of octagon hip and common rafters 5 and many other common timber cuts which are too numerous to enumerate, may with the scales here shown be readily accomplished. The use of the arm 13 in combination with the right angularly extending arm 41, as will be understood, 10 greatly facilitates the scribing of certain cuts which extend at right angles to each other, such as exemplified by the common foot and toe cuts 111 and 112. Also this right angular combination of arms is especially applicable to the scribing 15 of the rise and tread cuts of stair stringers.

It will thus be clear that the tool of my invention is well adapted to the accomplishment of the objects hereinbefore referred to.

I claim:

1. In a device of the character described, a plate providing a straight edge thereon arranged for abutment against a side of a timber, an arm having pivotal connection intermediate its length with said plate adjacent said edge and disposable 25 with said edge against said timber with a portion of said arm lying over a surface of said plate and a second portion extended from said edge to overlie a surface of said timber for scribing same, said second arm portion being provided with a 30 groove extending longitudinally thereof and opening at the side thereof and in a plane parallel to said timber surface, and a member slidably carried in said groove and provided with an angular portion thereof extending through said groove to 35 overlie said timber surface.

2. In a device of the character described, a plate providing a straight edge thereon arranged for abutment against a side of a timber, an arm having pivotal connection intermediate its length 40 with said plate adjacent said edge and disposable with said edge against said timber with a portion of said arm lying over a surface of said plate and a second portion of said arm extending from said edge to overlie a surface of said timber for scrib- 45 ing same, said second arm portion being hollowed and having a slot opening along a side thereof and in a plane parallel to said plate, and a member slidably enclosed in said second arm portion and having a right angularly extending end ex- 50 tension extending through and from said slot.

3. In a device of the character described, a plate providing a straight edge thereon arranged for abutment against a side of a timber, an arm having pivotal connection intermediate its length 55 with said plate adjacent said edge and disposable with said edge against said timber with a portion of said arm lying over a surface of said plate and a second portion of said arm extended from said edge to overlie a surface of said timber for scrib- 60 ing same, said second arm portion being provided with a groove opening to opposite sides of the arm and extending longitudinally therealong, and a member slidably carried in said groove and having a portion thereof extending angularly from 65 said arm, said member being arranged for reversal in said groove with said member portion being selectively extendable from either of said opposite arm sides.

4. In a device of the character described, a 70 plate having a straight edge arranged for abutment against the side of a timber, an arm pivoted to said plate for movement thereover and over said timber and provided with a groove opening to the side thereof, a slide member mounted in 75

said groove and provided with a right angular extension extending from said groove, and a sight opening in said arm adjacent said edge for measuring the distance from said edge to said extension along said arm.

5. In a device of the character described, a plate having a straight edge arranged for abutment against the side of a timber, an arm pivoted to said plate for movement thereover and over 10 said timber and provided with a groove opening to the side thereof, a graduated slide member

mounted in said groove and provided with a right angular portion extending through said groove, a sight opening in said arm adjacent said edge, and graduations on said arm adjacent said opening and arranged for alignment with said edge 5 and the graduations on said slide member.

6. In a device as characterized in claim 4 including, means extending into said opening and securing said arm and slide member against relative movement.

BERNARD J. DAVIS.
